UNITED STATES PATENT OFFICE.

JESSE E. GEISSINGER, OF SHALER TOWNSHIP, NEAR MILLVALE, ALLEGHENY COUNTY, PENNSYLVANIA.

CLOTHES-WRINGER ATTACHMENT.

1,371,156.

Specification of Letters Patent.

Patented Mar. 8, 1921.

Application filed July 19, 1920. Serial No. 397,306.

To all whom it may concern:

Be it known that I, JESSE E. GEISSINGER, a citizen of the United States, residing in Shaler township, near Millvale, in the county 5 of Allegheny and State of Pennsylvania, have invented certain new and useful Improvements in Clothes-Wringer Attachments; and I do declare the following to be a full, clear, and exact description of the invention, such as will enable others skilled in the art to which it appertains to make and use the same.

This invention relates broadly to clothes-wringers and more specifically to an attachment therefor which is designed to feed clothes between the press-rolls, thus making it possible to perform this work in an entirely safe way and to do away with the old method of feeding the clothes between the 10 rolls by hand, which practice oftentimes causes the operator's fingers to be caught between the rolls and mashed or otherwise injured.

An object of the invention is to provide 15 an attachment of the above mentioned class which is such that it will permit the clothes to be fed between the rolls from either side of the wringer.

Another object of the invention is to provide 20 an attachment of this class which is such that when the clothes are being fed from one side of the machine, the edge of the attachment on the opposite side of the machine will be automatically moved to ineffective 25 position and as soon as the attachment is released, the then ineffective edge thereof will automatically move into close proximity to the adjacent press-roll and will act as a scraper and prevent the clothes from 30 winding on this roll.

Other objects and advantages of the invention will be apparent during the course 35 of the following description.

In the accompanying drawings forming 40 a part of this specification and in which like numerals are employed to designate like parts throughout the same:

Figure 1 is an elevational view, with parts 45 in section, of a clothes wringer equipped with an attachment constructed in accordance with my invention.

Fig. 2 is a sectional view taken on the plane of the line 2—2 of Fig. 1, looking in the direction of the arrows, the feeder being 50 shown out of use.

Fig. 3 is a view like Fig. 2 showing the position the feeder assumes when in use.

Fig. 4 is a view taken on the line 4—4 of Fig. 1.

In the drawings, wherein for the purpose 60 of illustration is shown a preferred embodiment of my invention, the numeral 1 designates a clothes wringer of the power-driven type, the same including a downwardly inclined feed-board 2 and a pair of press-rolls 65 3 which are journaled in the uprights of the wringer frame which carry cog-wheel guards 4. These guards 4 are the usual ones provided for a wringer of the type shown, and since they are in close proximity to the 70 press-rolls, I find it convenient to use them as bearings for the shaft of my device, however, I wish it to be understood that I am not to be restricted to the use of these particular bearings, because any other suitable 75 bearings may be employed according to the type of wringer upon which my improved device is installed. The upper portions of these guards are recessed and serve as bearings for the journals 5 of the shaft 6 of my 80 improved device, the major portion of this shaft being of non-circular formation. Secured in any suitable manner on this shaft 6 is a clothes feeding member 7 of a size to almost encompass the upper press-roller, 85 this construction permitting the longitudinal edges of this member to be disposed on opposite sides of this roller in a position which makes it possible to feed the clothes from either side of the wringer. The member 90 7 may be of any suitable construction, but I prefer to employ a plate, the same being substantially semi-circular and being of a diameter greater than the diameter of the upper press-roller so that its longitudinal 95 edges will be in a proper position to be brought between the rolls for forcing the clothes therethrough. For the purpose of actuating the feeder, suitable handles 8 are supplied.

Oftentimes the action of the press-rolls is such that when the clothes are fed through from one side, they wind around the upper press-roll on the discharge side, which is of course undesirable and sometimes causes 105 the operator's fingers to become injured in the endeavor to unwrap the clothes from this roller. I have devised means for preventing the clothes from wrapping about the press-rolls in this manner. This means, 110

by preference, comprises two coiled springs 9 and 10, each of which has one of its ends secured to the shaft 6 and is provided at its opposite end with an eye 11 adapted to be connected by means of a thumb screw 12 to one of the uprights of the wringer frame. Only one of these springs will be used at a time. It is to be noted that each of the springs is coiled in a direction opposite to that of the other and one of the springs rotates the shaft in one direction while the other rotates it in an opposite direction. With this construction it will be seen that after the clothes feeding plate 7 has been manually moved to force the clothes between the press-rolls and is released, the then active coiled spring will rotate the shaft in such a manner as to bring the previously ineffective edge of the feed plate into close proximity to the upper press-roll as disclosed in Fig. 2, in which position it will act as a scraper and prevent the clothes from winding about this roller. If the clothes are being fed from the right-hand side of the wringer, the coiled spring 9 will be made to be effective, that is, the eye 11 of this spring will be anchored by means of the screw 12. When the parts are in this position, the feeding member 7 will normally assume the position shown in Fig. 2. On the other hand, if it is desired to feed the clothes from the opposite side of the wringer, it will also be desirable to have the feed-plate moved in an opposite direction. In order to do this, it is only necessary to remove the screw 12 from the position in which it is shown, and pass it through the eye 11 of the spring 10 and anchor this end of this spring so that it will become effective and the spring 9 will become ineffective.

It is not desirable to have the longitudinal edge of the feed-plate to move into contact with the upper press-roll. To overcome this, I provide means for limiting the rotation of the shaft 6. This means may be of any suitable construction, however, when the device is used with the type of bearing shown, I merely form opposed shoulders 13 at the upper portion of these bearings, with which shoulders the stop pins 14 co-act. The shoulders will be so spaced that the proper amount of rotation will occur to prevent the feed-plate from coming into direct contact with the upper press-roll.

I desire to state at this point, I have disclosed a similar device for the same purpose in my co-pending application Serial No. 388,871, filed June 14, 1920. By referring to this application it will be seen that the device therein shown is quite different in construction and does not accomplish the same results that the present device does. One of the main differences between the two devices resides in the fact that the present device permits the clothes to be fed from

either side of the wringer, which result cannot be obtained with the other device. Also, another difference resides in the fact that provision is made in the present device for preventing the clothes from wrapping around the press-rolls as oftentimes occurs.

In use, the clothes will be fed from either side of the machine according to the direction of rotation of the press-rolls. This is a point and advantage to be carefully considered in that it permits the operator to feed the clothes from either side of the machine. As is customary, the clothes are first laid on the inclined feed-board 2 and moved up into contact with the press-rolls as shown in Fig. 2. When the clothes are in this position, adjacent handle 8 is gripped and the feed member 7 moved so as to bring the then ineffective longitudinal edge of the feed-member 7 against the clothes as shown in Fig. 3. After this, a slight forward push of the feed-member will force the clothes between the rolls far enough to cause them to be gripped by the latter and carried through in the usual manner. The handle 8 is then released and the then effective coiled spring will automatically move the opposite longitudinal edge of the feed-member into close proximity to the opposite side of the upper press-roll, in which position it will act as a scraper in the manner already described.

A device constructed in accordance with the foregoing description will be found extremely advantageous, and will prevent the operator from injuring her fingers, as is a common occurrence. The construction which I employ is extremely simple, inexpensive, easy to manipulate and is highly effective in operation.

A careful consideration of the foregoing description taken in conjunction with the accompanying drawings will enable persons skilled in the art to which this invention appertains to obtain a thorough understanding of the same. In view of this, further description is thought unnecessary.

It is to be understood that the form of my invention herein shown and described is to be taken as a preferred form of the same, and that various minor changes in the shape, size, and arrangement may be resorted to without departing from the spirit of the invention or the scope of the subjoined claims.

I claim:

1. The combination with a clothes-wringer including a pair of press-rolls; of a substantially semi-circular clothes feeding member movably mounted on the wringer over the upper press-roll, said member being of a size to almost encompass said upper roll and having its longitudinal edges disposed opposite the meeting points of the two rolls, permitting the clothes to be fed from either side of the wringer.

120

130

2. The combination with a clothes-wringer including a pair of press-rolls, of a movably mounted clothes feeding member arranged adjacent one of said press-rolls, and having 5 its longitudinal free edges spaced from the intake and discharge points of said press-rolls, permitting clothes to be fed from either side of the wringer, one edge of said member being moved away from the rolls 10 when the remaining edge is forced between the rolls.

3. The combination with a clothes-wringer frame including a pair of press-rolls; of a shaft rotatably mounted on the frame, a 15 plate of semi-circular form secured intermediate its longitudinal edges on said shaft so as to almost encompass one of said press-rolls whereby its ends will be in position to feed the clothes from either side of the 20 wringer.

4. The combination with a clothes-wringer including a pair of press-rolls; of a rock shaft carried by the wringer, a manually actuated member for feeding the clothes 25 from either side of the wringer, said member being secured at a point centrally between its free edges on said shaft to permit one edge to be moved to ineffective position when the other edge is moved to 30 effective position.

5. The combination with a clothes-wringer including a pair of press-rolls; of a clothes feeding member movably mounted on the wringer adjacent the upper press-roll, said 35 member being of a size to almost encompass said upper roll and having its longitudinal edges in a position opposite the intake and discharge points for feeding the clothes from either side of the wringer, and means 40 associated with said member to automatically move one edge thereof away from the adjacent roll and simultaneously bring the other edge into close proximity with the roll to act as a scraper and prevent the 45 clothes from wrapping around this roll.

6. The combination with a clothes-wringer frame including a pair of press-rolls; of a

clothes feeding member movably mounted on the frame close to one of said rolls, said member having its opposite longitudinal edges 50 arranged on opposite sides of said rolls, and a coiled spring associated with said member for normally retaining one of its longitudinal edges in close proximity to the upper press-rolls and moving the other edge 55 away from the rolls.

7. The combination with a clothes-wringer including a pair of press-rolls; of a shaft journaled on the wringer, a clothes-feeder carried by the shaft, said feeder having 60 its opposite longitudinal edges positioned to be brought into close proximity to said press-rolls, a coiled spring having one of its ends secured to and coiled around said shaft and having an attaching eye at its 65 opposite end for connection to one of the uprights of the wringer frame, said spring serving to automatically move one edge of the feeder into close proximity to the adjacent press-roll. 70

8. The combination with a clothes-wringer including press-rolls; of a shaft rotatably mounted on the wringer, a clothes-feeder carried by the shaft, having its effective edges positioned on opposite sides of the 75 press-rolls, a pair of springs secured at one of their ends to said shaft and coiled in opposite directions around the latter so as to rotate it in opposite directions, and a member fastening the free end of one of the 80 springs to the wringer frame, thus permitting a single spring to be effective at one time.

9. The combination with a clothes-wringer including press-rolls; of a shaft rotatable 85 on said wringer, a clothes feeding member carried by the shaft, and a lateral projection at each end of the latter, and shoulders for the projections to engage so as to limit the rotation of the shaft. 90

In testimony whereof I have hereunto set my hand.

JESSE E. GEISSINGER.
